UNITED STATES PATENT OFFICE.

WALTER CHIPPERFIELD, OF ROMFORD, ENGLAND.

DRAWER-LOCKING MECHANISM.

1,370,089.

Specification of Letters Patent.

Patented Mar. 1, 1921.

Application filed January 5, 1920. Serial No. 349,590.

To all whom it may concern:

Be it known that I, WALTER CHIPPERFIELD, a subject of the King of Great Britain, residing at Roneo Works, Romford, in the county of Essex, England, Great Britain, have invented new and useful Improvements in or Relating to Drawer-Locking Mechanism, of which the following is a specification.

10 The present invention relates to metal cases containing one or a plurality of sliding structures, hereafter termed drawers, and more particularly relates to mechanism by which the drawers in their closed positions are locked and unlocked.

15 The object of the present invention is to improve the construction and operation of the locking mechanism for such drawers, and to provide an improved detent device, 20 and moreover to render the construction such that it is particularly adapted for use with cases, the composing parts of which can be readily separated for packing and transport, and which can be easily put together.

25 The present invention will be described with reference to the accompanying drawings, whereon Figure 1 is a sectional side elevation of the upper part of a case fitted with the locking mechanism according to 30 the present invention, Fig. 2 being a front elevation, partly in section, of the parts shown at Fig. 1, and Figs. 3 show a detent lever detached in side elevation, end elevation and plan.

35 According to this invention a two armed lever 1, of bell crank character, is fulcrumed on a horizontal pin 2, carried by a bracket 3 fixed to and pendent from the interior of the top of the case 4, one arm of 40 the lever 1 extends downward and its end is pivotally connected to the rear end of the sliding rod 5, whereby the inner end of the latter is supported while the forward end of said rod 5 extends through a slot in the 45 front wall of a downward flange 6 composing part of the top of the case 4, and exteriorly the rod 5 is fitted with a knob or handle 7.

The second arm of the bell crank lever 1 50 extends rearwardly and about horizontally and is formed with an open forked end; the upper end of the vertical locking rod 8 carries a forwardly extending bracket 9 having a horizontal pin 10 over which the forked end of the lever 1 is adapted to straddle for

moving the rod 8 vertically as the rod 5 is slid in and out. By this arrangement a rearward movement of the sliding rod 5 will rock the lever 1, and raise the locking rod 8 to lock the drawers, and a forward movement of the sliding rod 5 will permit the locking rod 8 to descend and unlock the drawers.

Fixed to the interior of the flanged top of the case 4, at the front, is a bracket 11, 65 having two upward arms, see Fig. 2, between which the horizontal pivot 12 is carried, and the pivot 12 passes above the upper edge of the sliding rod 5, while the latter extends between the arms of the bracket 11. Carried by the said pivot 12 is a detent lever 13, a rearwardly extending arm of which is fixed to one end of a helical spring 14, the other end of the spring being fixed to the sliding rod 5, so that when the sliding 70 rod is slid inward to locking position, the spring 14 is in tension, but in view of the fact that the pivoted lever 1 which the rod 5 operates causes but little friction, and also that the weight of the locking rod is counterbalanced by a light spring, such as 15, the spring 14 of the sliding rod 5 need not be very strong.

The pivoted detent lever 13 to which the spring 14 of the sliding rod 5 is connected 85 at the front of the case 4 has an extending arm 16, Fig. 3, forward of its pivot, and a notch is formed in the upper edge of the sliding rod 5 into which the lateral arm 16 of the detent lever takes, as shown at Fig. 1, 90 when the rod 5 is pushed home to locking position and by which it is held.

The detent lever 13 rearward of its pivot has a second lateral arm 17, Fig. 3, which extends over a member such as 18, Fig. 2, 95 which member 18 can be raised by a key inserted into the front of the case 4; when the member 18 is so raised the detent lever 13 is rocked upward about its pivot, and its detent arm 16 is lifted from the notch of the sliding rod 5, and the latter moves forward under the action of the springs 14, 15 aforesaid, the bell crank lever 1 is rocked, and the drawers are unlocked.

The mechanism described is particularly 105 well suited for cases which can be disassembled for transport and again built up where required, because the sliding rod 5 the detent lever 13 and its locking mechanism, and the bell crank lever 1 are all carried 110

and fixed in the downwardly flanged top of the case 4 which is constructed separately from the sides 19, and when such cases are being assembled the rear end of the top can 5 be slid into position so that the fork of the bell-cranked lever 1 automatically engages the pin 10 carried by the upper end of the locking rod 8, and the top of the case 4 can be brought down to proper position 10 and secured to the sides.

Having thus described my invention what 1 desire to secure by Letters Patent of the United States is as follows:

The combination with a casing having a 15 separable cover and drawer-locking means, including a rod vertically slideable in said casing, of means carried wholly by the cover for operating said rod, said means compris-

ing a bell-crank lever pivoted on the cover and having a forked end for engagement with said vertical rod, a rod horizontally slideable in said cover and pivotally secured to said bell-crank, means for maintaining said rod in locking position, said means comprising a detent pivotally mounted on 20 said cover and having a transverse arm at one side thereof adapted to engage a recess in said horizontally movable rod, a spring secured to said detent and rod for retaining said arm in engagement with said recess, 25 and means for disengaging the arm from the recess and including a transverse arm at the opposite side of the detent.

In testimony whereof I have signed my name to this specification.

WALTER CHIPPERFIELD.
